Samuel H. Allen's Horse Power
Patented Patent

The following is referred to in their Letters Patent and making part of the same containing a description of the mode of using the same. I claim for myself all of the improvement in the machine called a Horse Power.

To all whom it may concern

Be it known that I, Samuel H. Allen of Saratoga Springs in the County of Saratoga, (and State of New York,) have invented an improvement in constraining the horses usually called a horse power and that the following is a full and exact description thereof. The Horse power which I employ is intended to be portable & constructed that it may be easily transported from one place to another (and which requires no time for a horse, or mule, to run round by the walking of the horses in a circle, although I do not intend to confine myself to any particular size or any of the various parts.) I will for the sake of description, give the proportions which I have found to answer well in practice. I make a frame or box about six feet long four sixteen inches in height. The end pieces of which I plank three feet long at their lower edges, and two feet 8 inches at their upper. The sides have four steps in about two inches. The sides may be of two inch planks and must be securely fastened to the ends. This box is to contain the driving wheel and pinion, in their vertical shaft running in suitable boxes, to receive them boxes containing the whole pieces of timber to form along the upper and lower sides of the box. The upper frame may be 3 by 8 inches flush with the top and bottom and keyed through the ends, so that the edges must reach just to the center of the box, as the upper bearing or bights of the shafts are to be placed about the lower timber so three by nine inches and twelve feet long, as it is to extend upright without the box being secured to one end of it like the upper timber and notched in, and secured to the other end. The bights of the first driving wheel may be about 4 inches square (and above above the top timber about twelve, when it is a little to force to move the box or cart, to which the box is to be secured. This shaft is made of cast iron and has a flat with a flange next to the box to which the arms of the wheel to be previously secured, are secured.

The wheel is about thirty in diameter (and stands near to the house and of the
shaft). The lower driving wheel is about 26 inches in diameter, it stands
above the first driving wheel, and has on its shaft a pinion of about one-fifth
of the size of the first wheel, which meshes into it. The third shaft has a pinion
of about one-fifth of the size of the second wheel, which meshes into its. On the
lower end of this third shaft, there is a bevel or counter wheel, which may be
about 24 inches in diameter, its teeth project downward, and mesh into a
pinion about one-fifth of its size. This pinion is fixed upon an iron shaft,
which runs horizontally, near to the ground, and extends along the lower tim-
ber, six feet without the bay, upon which carries on its extreme end a
wheel of eighteen inches in diameter, from which a band extends to a thresh-
ing machine, small quill mill, or any other machinery to which such a
horse power is adapted. To receive this horizontal shaft, the edge of the
hill, or projecting piece of timber is rebated, or hollowed out on its under
side by which means it is protected from injury by the feet of the horse,
or from other causes. Instead of making the lower or hill timber, in
one piece, it may be made to consist of two bay, and be removed along
with the horizontal shaft, when required. The wheel before named, con-
sists of cast iron rims with arms made of wood. These arms are formed
of two pieces of hard stuff, or pitch, halbed together in the middle, the tim-
ber should be about 3 by 8 inches. The shaft passes through a mortise in
the centre of the arms; and they are secured by bolts to the flanges, or disks,
upon the shaft; the ends of the arms may then be turned off to fit the inner
part of the rim of the wheel. The rims are strong Stanley's flaunch which
projects inward serving as a bearing for the arms (and also to hold them to),
a projection is cast on each side of the arms, within the rims to confine
them in width, and save them from splitting; when the horse power is
to be used, it is placed upon the ground, in which it will be necessary
to make a small excavation to receive the lower part of the wheel. Four
stakes are to be driven into the ground at the four corners of the bay, and two
chains fastened on these by means of weags, passing over the bay, near
each end, will render it perfectly safe. That follows as new and
very interesting, is the manner of making the wheel, as before mentioned.

with wooden arms and cast iron rims, by which means they are affixed,
are lighter and may be more easily repaired in the case of the
breaking of a cog, than when the whole is made of cast iron. Also claims
the convenience of leaving the horizontal shaft from injury, (and so that the
lens may pass over it, with little or no obstruction.)
